US00D837038S

(12) **United States Design Patent** (10) **Patent No.:** **US D837,038 S**
(45) **Date of Patent:** **** Jan. 1, 2019**

(54) **INSULATION HANGER**(71) Applicant: **CERTAINTEED CORPORATION**,
Malvern, PA (US)(72) Inventors: **Jean-Philippe Ndobo-Epoy**, Westboro,
MA (US); **Jerome Arul**, Providence, RI
(US); **Andrew Clyde Brandt**,
Pottstown, PA (US); **Todd P. Dinoia**,
Littleton, MA (US); **Luc Pierre Vitry**,
Philadelphia, PA (US); **Conor Patrick
McDonald**, Boston, MA (US)(73) Assignee: **CERTAINTEED CORPORATION**,
Malvern, PA (US)(**) Term: **15 Years**(21) Appl. No.: **29/599,314**(22) Filed: **Mar. 31, 2017**(51) LOC (11) Cl. **08-05**

(52) U.S. Cl.

USPC ..... **D8/354**(58) **Field of Classification Search**USPC D8/354; D25/119, 121, 122
CPC F16L 59/12; E04B 1/7666; E04B 1/7629;

Primary Examiner — George D. Kirschbaum*Assistant Examiner* — Maria J Edwards(74) *Attorney, Agent, or Firm* — Abel Law Group, LLP;
Thomas Osborn(57) **CLAIM**

The ornamental design for an insulation hanger, as shown and described.

DESCRIPTION

FIG. 1 is top perspective view of an insulation hanger showing our new design;

FIG. 2 is a side elevation view thereof;

FIG. 3 is a top elevation view thereof; and,

FIG. 4 is a back elevation view thereof.

The broken lines represent portions of the article and form no part of the claimed design.

1 Claim, 1 Drawing Sheet# US D837,038 S
